Inventor:

Byron B. Goldsmith.

James C. Norris.

UNITED STATES PATENT OFFICE.

BYRON B. GOLDSMITH, OF NEW YORK, N. Y.

PEN-HOLDER.

SPECIFICATION forming part of Letters Patent No. 434,265, dated August 12, 1890.

Application filed May 8, 1890. Serial No. 351,066. (No model.)

To all whom it may concern:

Be it known that I, BYRON B. GOLDSMITH, a citizen of the United States, residing at New York, in the county of New York and State 5 of New York, have invented new and useful Improvements in Pen-Holders, of which the following is a specification.

This invention has for its objects to provide novel means for ejecting pens from pen-holders; to provide novel means for forcibly ejecting pens from pen-holders by pressing on the tip end of the staff without moving or otherwise disturbing the position of the pen-retaining core, head, or tube, which is arranged 10 in the usual barrel of the holder, and to otherwise improve pen-holders. To accomplish these objects my invention involves the features of construction, the combination or arrangement of devices, and the principles of 15 operation hereinafter described and claimed, reference being made to the accompanying drawings, in which—

Figure 1 is a longitudinal sectional view of one type of pen-holder embodying my invention. Fig. 2 is a transverse sectional view taken on the line $x-x$, Fig. 1. Fig. 3 is a sectional view of one end portion of the pen-holder, showing a modification. Fig. 4 is a longitudinal sectional view of another type of 20 pen-holder embodying my invention. Figs. 5, 6, and 7 are similar views showing modifications in the construction of the pen-holder. Fig. 8 is a transverse sectional view taken on the line $y-y$, Fig. 6. Fig. 9 is a similar view 25 taken on the line $z-z$, Fig. 7. Fig. 10 is a similar view showing a sheath-covering to the barrel. Fig. 11 is a detail perspective view showing a modified form of pen-retaining core or head with my invention applied thereto. Fig. 12 is a detail sectional view showing another modification.

In order to enable those skilled in the art to make and use my invention, I will now describe the same in detail, referring first to 45 Figs. 1 and 2, where the numeral 1 indicates the hollow metallic staff or handle of a pen-holder having at one end a barrel 2, of rubber or other material, in which is placed the pen-retaining core, head, or split tube 3, of 50 any desired construction, to retain the pen when the latter is inserted between the barrel and the core, head, or split tube. The

pen-retainer is hollow and provided with longitudinal slots 4, extending the greater part of its length, and the barrel is furnished with 55 longitudinal grooves forming guideways 5, which are coincident with the slots in the pen-retainer. The pen-ejector 6 is arranged within and slides rectilinearly along the pen-retainer, and is cruciform in shape, forming 60 radial wings 7, which extend through the slots 4 and enter the guideways 5, whereby the ejector is guided in its rectilinear movement. The ejector is attached to a longitudinal stem 8, placed axially in the staff or handle and 65 connected with a movable part of the latter, which part, as shown in Fig. 1, is composed of a shell or finger-piece 9, movable lengthwise in the main section of the staff or handle and pressed outwardly by a suitable spring 10 for 70 retracting the ejector toward the inner end of the pen-retainer. The wings of the ejector extend across the space provided for the insertion of the pen-butt, and consequently by 75 pressing upon the movable part 9 at the tip end of the staff or handle the ejector is advanced and strikes the pen-butt, thereby 80 positively forcing and discharging the pen from between the split tube or pen-retainer and the barrel. This ejection of the pen is 85 effected without in any manner disturbing the position of the pen-retainer, and hence the invention is applicable to ordinary pen-holders wherein the split tube or pen-retainer stands immovable as regards longitudinal 90 movement in the barrel. In this respect my invention differs from that type of pen-holders wherein the pen is held between the barrel and a cylindrical head or plug secured to a spring-retracted stem and moved outward by 95 pressing upon the stem to release the grip-action of the head or plug on the pen-butt.

In Fig. 3 the barrel 2 is of wood strengthened by a ferrule 12 and lined with metal, as at 13, while in Fig. 4 the main section of the staff or handle is of wood, and the barrel 2 is formed by drilling or boring a cylindrical recess therein.

In Fig. 5 the barrel 2 may be of rubber or wood, and at its inner end is formed or otherwise provided with a tubular extension 14, in which is adapted to slide lengthwise the movable part of the staff or handle, which movable part is composed of the metallic or other

tube 15, carrying the wooden or other handle or staff-body 1, to which the ejector-stem 8 is attached.

In Fig. 6 the pen-holder is the same as in Fig. 5, except that the barrel 2 is of metal, while in Fig. 7 the pen-holder is the same as in Fig. 6, except that the ejector comprises a single wing, in which construction the barrel will have but one guideway 5 and the pen-retainer one slot 4. If the barrel be made as a sheet-metal tube, the guideway 5 (one or more) may be formed by striking up hollow ribs on the barrel, as in Figs. 6, 7, 8, and 9, or the guideway 5 (one or more) may be formed by a slot in the barrel, as in Fig. 10, and if such slots be found objectionable by some persons they can be covered and concealed by a metallic, rubber, paper, or other sheath 16 slipped over the barrel, as indicated by Fig. 10.

Instead of the elastic or yielding pen-retainer being made to retain the pen between the outer surface of the retainer and the inner surface of the barrel, the pen-retainer may be composed of a longitudinally-slotted plug or core 17, Fig. 11, into the slits 18 of which the pen-butt is inserted. This plug or core is adapted to be fixed in a stationary position in a pen-holder barrel, as usual, and the wings of the ejector extend into the slits 19 of the plug or core, or such wings of the ejector could be made to slide in the slits 18. The remaining parts of the pen-holder may be of the construction shown by the remaining figures of the drawings.

In Fig. 12 I exhibit the ejector 6 as composed of a sleeve sliding between the slotted pen-retainer 3 and the pen-holder barrel 2. If this construction be adopted, the sleeve will connect with the stem 8 by arms 20, moving in the slots of the pen-retainer.

The spring-retracted ejector advanced by pressing on the outer or tip-end portion of the staff or handle while the pen-retainer stands stationary is an improvement on that type of pen-holders wherein a pen-ejector is pushed outward and inward by the fingers.

Having thus described my invention, what I claim is—

1. The combination, with the internal pen-retainer of a pen-holder, of an ejector sliding in and guided by the pen-retainer to strike the pen-butt and forcibly eject the pen, a spring for retracting the ejector, and means for advancing the ejector, substantially as described.

2. The combination, in a pen-holder, of a staff or handle comprising a barrel and a movable part or finger-piece, a pen-retainer in the barrel, an ejector movable in but independent of the pen-retainer, a stem connecting the ejector with the movable part or fin-

ger-piece, and a spring for retracting the ejector, substantially as described.

3. The combination, in a pen-holder, of a staff or handle comprising a barrel and a movable finger-piece at the tip end of the staff or handle, a spring acting to press the finger-piece outward, a pen-retainer fixed inside the barrel, an ejector movable independent of the pen-retainer and guided by the latter to strike the pen-butt and forcibly eject the pen, and a stem connecting the ejector with the finger-piece, substantially as described. 75

4. The combination, in a pen-holder, of a longitudinally-slotted pen-retainer located in the holder, and an ejector sliding within the pen-retainer and comprising a wing moving in a slotted part of the pen-retainer in the path of the pen-butt to strike and forcibly eject the pen, substantially as described.

5. The combination, in a pen-holder, of a staff or handle having a barrel, a longitudinally-slotted pen-retainer arranged in the barrel, a winged ejector sliding independent of the pen-retainer and extending into a slotted part thereof in the path of the pen-butt to strike the latter and forcibly eject the pen, and means for advancing the ejector, 90 substantially as described.

6. The combination, in a pen-holder, of a staff or handle comprising a barrel and a movable part or finger-piece, a longitudinally-slotted pen-retainer in the barrel, a winged ejector sliding independent of the pen-retainer and projecting therethrough into the path of the pen-butt, and a stem connecting the ejector with the movable part or finger-piece, substantially as described. 100

7. The combination, in a pen-holder, of a staff or handle comprising a barrel and a movable part or finger-piece, a longitudinally-slotted pen-retainer in the barrel, a winged ejector sliding in the pen-retainer 105 and projecting therethrough into the path of the pen-butt, a stem connecting the ejector with the movable part or finger-piece, and a spring for retracting the ejector, stem, and finger-piece, substantially as described. 110

8. The combination, in a pen-holder, of a staff having a barrel, a hollow longitudinally-slotted pen-retainer arranged in the barrel, and a winged ejector sliding inside the pen-retainer and projecting therethrough 115 into the path of the pen-butt, substantially as described.

In testimony whereof I have affixed my signature in presence of two witnesses.

BYRON B. GOLDSMITH.
